UNITED STATES PATENT OFFICE.

CHARLES E. TIBBLES, OF CHICAGO, ILLINOIS, ASSIGNOR TO THE TIBBLES MANUFACTURING COMPANY, OF SAME PLACE.

FEED-MOTION FOR SEWING-MACHINES.

SPECIFICATION forming part of Letters Patent No. 328,542, dated October 20, 1885.

Application filed May 14, 1885. Serial No. 165,412. (Model.)

To all whom it may concern:

Be it known that I, CHARLES E. TIBBLES, of Chicago, in the county of Cook and State of Illinois, have invented certain Improvements 5 in Feed-Motions for Sewing-Machines; and I hereby declare the following to be a full, clear, and exact description of the same, reference being had to the accompanying drawings, making part of this specification, in 10 which—

Figure 1 is a bottom plan view of the bed-plate of the machine and attached mechanisms. Fig. 2 is a detail elevation of the stitch-controlling device. Fig. 3 is a side elevation of 15 the feed-bar, feed-points, and raising and lowering cam, the driving-shaft being in section. Fig. 4 is a bottom plan of the feed-bar, its fastenings, and driving-shaft. Fig. 5 is a side elevation of the bar and cam for working the 20 lever that reciprocates the feed-bar. Fig. 6 is a plan of the same bar shown in Fig. 5, and a sectional view of the mechanism to change the throw of the cam that operates the bar. Fig. 7 is an end view of a sleeve on the driving-shaft provided with a pin to change the 25 set of the cam which reciprocates the feed-bar. Fig. 8 is an end view of the hub on the cam to reciprocate the feed-bar, and a section through the hub and cam. Fig. 9 is a plan 30 and section of the vibrating lever that moves the feed-bar. Fig. 10 shows details to be referred to.

The object of my invention is to provide a feed-motion for sewing-machines which can be 35 set to feed the work both to and from the operator at will, and will also feed the work always from the operator, regardless of which way the driving-wheel may be turned.

My invention also has for its object to take 40 up and compensate for all lost motion produced by wear between the working parts of the feed-motion.

My invention consists in various details of construction and combinations of devices, as 45 hereinafter fully described, and specifically pointed out in the claims, being improvements on the invention described and claimed in my application filed March 11, 1884, and bearing Serial No. 123,834.

In order that those skilled in the art may 50 make and use my invention, I will proceed to describe the exact manner in which I have carried it out.

In the said drawings, A is the bed-plate of the machine, and B is the driving-shaft. On 55 the driving-shaft, by means of set-screw 2, is adjustably secured a sleeve, B', through which passes a plunger or pin, b'', having a short rectangular arm, b''', on its outer or protruding end to engage in notches n n', of different 60 depths, and retract the pin against spring n'' when desirable, for a purpose hereinafter set out.

On driving-shaft B, adjacent to sleeve B', is the cam e, which through intermediate connections reciprocates the feed-bar. This cam is provided with a cylindrical hub, e', the end of which is cut away to a short depth around one-half of the face, forming a depression, e''', having at one end the semicircular shoulder 70 e'', and at the other end a hole, b'', of a proper size to receive and engage with the inner end of pin b'', whereby the hub and attached cam and sleeve B may be locked together, for a purpose hereinafter set out.

The cam e lies between two downwardly-projecting adjustable arms, c c, secured to a pitman-bar, E, which passes on one side of the shaft without touching it, against which arms said cam strikes to move bar E back and forth, 80 neither bar nor cam contacts c c touching the shaft proper. The arms c have rectangular slotted heads c', through the slots of which pass screws securing the arms to bar E, and the slots afford a ready means of setting up 85 the arms to the cam to compensate for wear.

The bar E has one end sustained in a box, e', secured to the bed-plate, said box having a central adjusting-screw, e'', which bears against an interior loose flat gib or plate, e'', 90 on which rests the end of bar E, the feeding forward of the screw e'' serving to push the gib against the bar E and bring it to a bearing in order to compensate for wear. The other end of bar E rests on the top of one end of the vibrating lever H, and engages with it by means of stud h and hole h', the other end of said lever H being provided with a slot, h'',

which engages a vibrating button or stud, *g*, on one end of the feed-bar *F*. The stitch-changing bar *G* carries the movable fulcrum around which lever *H* vibrates. This fulcrum consists of a box, *I*, which straddles bar *G* and fits exactly over the edges of lever *H*, the said box being secured to bar *G* by means of a headed screw, *i*, about which the box vibrates.

10 Interposed between bar *G* and lever *H* is a gib, *i'*, against the lower side of which bears a screw, *i*', which passes through the center of screw *i*, tapped for that purpose, and is provided with a jam-nut. Turning screw *i*' inward forces gib *i'* against lever *H*, and always brings it up so as to make the bearing perfect, and thereby compensates for wear.

15 The change in the position of the movable fulcrum by the longitudinal movement of the bar *G* determines the length of the throw of the feed-bar, and consequently the length of the stitch, after the well-known manner in such devices, with the exception that at the longest throw of the feed-bar the movable fulcrum is at the center of the lever *H*, so that, whatever be the length of stitch, *I* at all times maintain a powerful leverage to throw the feed-bar.

20 The feed-bar *F* is sustained and slides in rectangular supports or hangers *f*', secured to the race-rib by headed screws passing through slots 4 4, the slots enabling a ready adjustment of the bearings of the feed-bar against the rib, while gibs 5 5, inserted between the hangers 25 and the lower face of the feed-bar and set up by screws 6 6, allow a vertical adjustment of the feed-bar to take up lost motion or for other purposes.

25 The feed-points *F*' are secured to a sliding block, *F*'', which moves independently in vertical ways 7 7 in the feed-bar, and is actuated by cam *f* on the driving-shaft. In a recess in block *F*'' is a movable contact, *f*'', for cam *f* to strike, controlled by a screw, *f*''', to feed it 30 downward in order to take up lost motion.

35 It will be observed that in so far as the pitman-bar *E* is concerned it has no direct contact with the driving-shaft, and cam *e* only touches the arms *c* *c*, thereby avoiding any 40 wear whatever on the shaft or cams that cannot be compensated for by setting up said arms *c* *c*.

45 The pin *b*''' is of such a length as to enter well into hole *b*'', and yet not touch the bottom and crowd the cam to one side.

50 The cam is kept from slipping out of place by a flange, *t*, made on bar *E*, as well as by the hub *e*', if a hub be used; but other well-known means—as a collar and set-screw—may 55 be used on the shaft for the same purpose without departing from the spirit of my invention.

60 It is obvious that the sleeve *B*' may be made integral with the driving-shaft without departing from the spirit of my invention, and

also that hole *b*'' and recess *e*''' *e*''' may be made directly in the face of the cam instead of in an intervening hub, *e*'.

65 When the pin *b*''' has its lever *b*''' turned to drop into the deepest notch *n* in sleeve *B*', the spring *n*'' throws the inner end of the pin into the hole *b*'' in hub *e*'. The sleeve *B*' being fixed to the driving-shaft, this operation locks the cam *e* on the shaft rigidly without any lost motion, and in such a position that the center radius of its working-arc lies exactly at right angles to the center radius of the working-arc of the lifting and depressing cam *f*. In this position the cams will feed the goods in time toward the operator, when the driving-wheel is thrown toward the operator and feed the goods in time from the operator, when the driving-wheel is turned from the operator.

70 When it is desired to always feed the goods from the operator, regardless of the direction of the rotation of the driving-shaft, the pin *b*''' is withdrawn from hole *b*'', and lever *b*''' is turned into the shallower notch *n*', leaving the inner end of the pin *b*''' projecting into the depression *e*''', so that hub *e*' can move freely in either direction one-half a revolution, until it brings up either against shoulder *e*''' or the shoulder *e* at hole *b*''. When the driving-shaft is now turned in one direction, the friction checks the cam until the end of the pin abuts against the shoulder *e*''', when the cam *e* is carried along with the shaft by contact with the pin at a point quartering exactly across the position of cam *f*, and the machine 80 feeds from the operator in time. When the driving-shaft is rotated in the opposite direction, the friction checks cam *e* for half a revolution, until the end of the pin *b*''' strikes the shoulder *e* at hole *b*'', and carries said cam 85 along, quartering in the opposite direction from that maintained while the pin was against shoulder *e*''', and also quartering exactly across cam *f*, and in a position consequently to still feed the work from the operator in time.

90 Having thus described my invention, what I claim as new, and desire to secure by Letters Patent, is—

1. In a feed mechanism for sewing-machines, the feed-bar *F*, and cam *e*, for reciprocating the feed-bar, having hole *b*'' and semicircular depression *e*''', in combination with the stationary sleeve *B*', provided with movable pin *b*''', and the driving-shaft *B*, substantially as described.

115 2. The stitch-regulating bar *G* and vibrating lever *H*, in combination with box *I*, flat gib *i'*, screw *i*, and screw *i*', passing through screw *i* and abutting against gib *i'*, all constructed, arranged, and operated as described.

120 3. The driving-shaft *B*, sleeve *B*', provided with notches *n* *n*'', spring-pin *b*''', cam *e*, provided with hole *b*'' and depression *e*''', pitman-rod *E*, having adjustable contact-arms *c* *c*, vibrating lever *H*, provided with a movable-

130

fulcrum feed-bar, F, and stitch-regulating bar G, all constructed, arranged, and operated as set forth.

4. In a sewing-machine feed mechanism, the pitman-bar E and devices to support it entirely free of the driving-shaft, in combination with two laterally-adjustable contact-arms, c e, cam e, to reciprocate the feed-bar, feed-bar

F, and operating mechanism connecting the feed-bar and pitman-bar E, substantially as set forth.

CHARLES E. TIBBLES.
